United States Patent Office.

L. L. DAVIS, OF SPRINGFIELD, MASSACHUSETTS.

Design No. 3,195, dated September 22, 1868.

DESIGN FOR A SPIRIT-LEVEL.

The Schedule referred to in these Letters Patent and making part of the same.

TO ALL WHOM IT MAY CONCERN:

Be it known that I, L. L. DAVIS, of Springfield, in the county of Hampden, and Commonwealth of Massachusetts, have invented or produced a new Design for a Spirit-Level and Plumb, of which the following is a full, clear, and exact description, reference being had to the accompanying drawings, making a part of this specification.

In the drawings—

b represents the outer frame of the level, to which are added the bed-pieces *a a*.

f is the bubble-case frame, being circular in form, inside of which revolves or oscillates the bubble-case *d*.

Extending around upon the inside of the frame *b*, and also partially around the bubble-case frame *f*, is the additional frame or piece, *e*, and the space which this frame *e* encloses is filled up or occupied by the scroll or ornamental work *c c*.

What I claim as my invention, and desire to secure by Letters Patent, is—

The design or pattern for a spirit-level and plumb, herein set forth and shown.
